UNITED STATES PATENT OFFICE.

CHARLES A. SCHINDLER, OF WEST HOBOKEN, NEW JERSEY.

SIGNALING DEVICE.

1,046,225.

Specification of Letters Patent. Patented Dec. 3, 1912.

Application filed April 6, 1912. Serial No. 668,895.

To all whom it may concern:

Be it known that I, CHARLES A. SCHINDLER, a citizen of the United States, and a resident of West Hoboken, in the county of Hudson and State of New Jersey, have invented a new and Improved Signaling Device, of which the following is a full, clear, and exact description.

The invention relates to signaling devices, such as shown and described in the Letters Patent of the United States, No. 1,015,715, granted to me January 23, 1912.

The object of the present invention is to provide a new and improved signaling device, more especially designed for the use of chauffeurs and other drivers of vehicles, and arranged to enable the user to readily give an audible signal during the day and a visible signal during the night to a following vehicle whenever it is desired to turn out of the direction in which the vehicle is traveling or for other purposes.

In order to accomplish the desired result use is made of a glove provided on one finger with spaced contacts, either of which is adapted to be engaged by a circuit-closing contact on an opposite finger, the said contacts being in two electric circuits connected with a single source of electrical energy, one circuit containing an electric lamp and the other circuit containing an audible alarm.

A practical embodiment of the invention is represented in the accompanying drawings forming a part of this specification, in which similar characters of reference indicate corresponding parts in all the views.

Figure 1 is a perspective view of the signaling device; Fig. 2 is a diagrammatic view of the same; and Fig. 3 is an enlarged sectional side elevation of one end of the battery used for supplying electrical energy to the signaling device.

A glove A is provided at one side with a pocket B adapted to contain a dry battery C, of any approved construction, the body B being normally closed by straps D which when unfastened permit of conveniently opening the pocket B for removal of the dry battery C or replacing the same by a new one. One electrode of the dry battery C is connected with a circuit wire E connected by branch wires E', E'' with an electric lamp F, and an electric bell or a similar audible alarm G, and the other electrode of the battery C is connected by a wire E'' with a circuit-closing contact H arranged on

the thumb A' of the glove opposite the forefinger A² which contains spaced contacts H', H'', either of which is adapted to be engaged by the contact H on the operator moving the thumb A' and the finger A² correspondingly toward each other. The contact H' is connected with the electric lamp F and the contact H'' is connected with the audible electric alarm G so that when the operator moves the contacts H and H' in engagement with each other then the circuit for the electric lamp F is closed and the latter is lighted and burns until the contacts H and H' are separated. When the contacts H and H'' are moved in engagement with each other then the circuit for the audible electric alarm G is closed and consequently the said alarm is sounded, and when the contacts H and H'' are moved out of engagement the alarm ceases.

It is understood that in using the glove, the chauffeur or driver of the vehicle holds out the hand at one side of the vehicle whenever it is desired to make a turn to the right or to the left and while holding out the hand with the glove thereon the operator during the day can connect the contacts H and H' with each other so as to give an audible signal to the driver of the following vehicle, and during the night the contacts H and H'' are moved in contact with each other so as to cause the electric lamp F to turn, thus giving a visible signal to the driver of the following vehicle.

It will be noticed that by the arrangement described both kinds of signals as well as the source of electrical energy are mounted on the glove and either signal can be readily controlled by the user of the glove on moving the contact H in engagement with either contact H' or H''. If desired the source of electrical energy may be located in the vehicle but in this case the circuit wires are made in sections having separable buttons, the same as shown in the patent above referred to, so that further description of the same is not deemed necessary.

The battery C is provided with caps C' and C'' through which extend the wires E, E' to connect with the corresponding electrodes, and inside of each cap C' or C'' is arranged a block I, of elastic material, such as rubber, interposed between the cap and the shell of the battery so as to prevent the ends of the wires from being accidentally broken especially as such elastic blocks readily take

up undue vibrations incident to the operator manipulating the steering wheel or other devices of the vehicle while having the glove A on his hand.

5. The electric lamp F is preferably inclosed in an open face casing provided in its sides with openings for the passage of rays of light in a sidewise direction.

Although a glove is specifically mentioned 10 as the support for the signaling device, it is understood that any equivalent support may be used.

Having thus described my invention, I 15 claim as new and desire to secure by Letters Patent:

1. In combination with a glove, of a source of current, an electric lamp mounted on the glove, an electric audible alarm mounted also on the glove, circuit wires connecting the 20 said source of current with the said lamp and the said alarm, spaced contacts for the said circuit wires and arranged on certain of the fingers of the glove, and a circuit closing

contact mounted on another finger of the glove and adapted to engage either of the 25 spaced contacts to close the corresponding circuit.

2. In combination with a glove, of a battery mounted on the said glove, an electric lamp mounted on the glove, an electric audible alarm mounted on the glove, circuit wires connecting the said battery with the said lamp and the said alarm, spaced contacts for the 30 said circuit wires and arranged on one finger of the glove, and a circuit-closing contact on an adjacent finger of the glove and adapted to engage either of the said spaced contacts to close the corresponding circuit.

In testimony whereof I have signed my name to this specification in the presence of 40 two subscribing witnesses.

CHARLES A. SCHINDLER.
